SEAM LOCK FOR ROLL ROOFING

William Herron Robison, Sparta, Ill.

Application April 14, 1937, Serial No. 136,917

2 Claims. (Cl. 108—33)

This invention relates to roofing and more particularly to a construction of roofing constructed of flexible water proof sheet material commonly supplied in roll form; and an object of the present invention is to provide for the efficient closing and locking of the seam between the adjacent sheets of roll roofing material.

The invention together with its objects and advantages will be best understood from a study 10 of the following description taken in connection with the accompanying drawings wherein:—

Figure 1 is a top plan view illustrating the application of the invention.

Figures 2, 3, and 4 are detail sectional views 15 showing the several steps resorted to in closing or locking the seam in accordance with the present invention.

Figure 5 is a perspective view of a portion of one of the seam locking members.

Figure 6 is a similar view of a complementary 20 seam locking member.

Figure 7 is a perspective view of a portion of a roofing sheet showing the latter provided with an integral side web.

25 Referring to the drawings by reference numerals it will be seen that the roll roofing sheets are indicated by the reference numeral 5. These sheets 5 are formed from the usual material employed, preferably a flexible waterproof sheet 30 roofing material commonly made of a wool felt base impregnated with asphaltum or the like.

In accordance with the present invention each 35 roofing sheet 5 is provided with outwardly turned integral side webs adapted to cooperate with similar side webs of adjacent units to form standing seams. These webs are indicated at 6 and 7 and may be of any suitable type.

As shown clearly in Figures 2 to 4, inclusive, the webs 6 and 7 of adjacent sheets 5 have a fairly 40 close fit, and in accordance with the present invention the seam between the webs is closed and locked. To this end there is provided in accordance with the present invention an angle plate 8 which is secured to the sheet 5 adjacent the web 45 7 through the medium of fastening elements 9 with the vertical flange 10 of the locking unit 8 in intimate contact with the web 7 and extending for the full length of the web.

Complemental to the locking strip 8 is a locking plate or strip 11 which is also in the form of an angle plate and is secured to the sheet 5 adjacent

the web 6 thereof through the medium of nails or other suitable fastening elements 12.

The vertical flange 13 of the locking plate 11 is disposed against the inner face of the web 6 and said flange 13 is folded longitudinally upon 5 itself to provide an integral molding or binder 14 within the channel of which is accommodated the webs 6 and 7 and the flange 10 of the locking strip 8 as clearly shown in Figure 4.

The molding 14 will serve to draw the webs 6 10 and 7 of adjacent sheets 5 into intimate facial contact so that the webs 6 and 7 of adjacent sheets will have an intimate close fit, with the molding or binder part 14 of the seam lock serving to prevent water from passing between the 15 webs 6 and 7.

It is thought that a clear understanding of the construction, utility and advantages of an invention of this character will be had without a more detailed description.

Having thus described the invention, what is claimed as new is:—

1. Roll roofing embodying a sheet of roofing material having side webs extending upwardly therefrom, a metallic angle locking strip secured 25 in relation to said sheet and one web thereof with one flange of said locking strip in facial contact with said one web, and a complementary metallic, angle locking strip associated with said sheet and having a vertical flange in facial contact with the 30 adjacent web of the sheet and also having a downturned flange spaced longitudinally from the vertical flange and overlying the first mentioned locking strip upon an adjacent sheet of roll roofing to close and lock the seam between said adjacent 35 roofing sheets.

2. In combination with a sheet of roll roofing material having integral upstanding side webs, an angle strip secured to the sheet adjacent one edge thereof and having a vertical flange in facial 40 contact with the adjacent side webs, and a second angle strip secured to said sheet adjacent the opposite edge of the latter, and having a vertical flange in contact with the side web of the sheet, said flange having a down folded longitudinal 45 edge portion cooperable with the first mentioned angle member to flange the confronting webs of the two sheets in intimate contact between the said vertical flanges of the angle strips.

50

WILLIAM HERRON ROBISON.
